DESIGN FOR A COSMETIC CONTAINER

Edgar E. Kahn and Louis Kanner, New York, N. Y.

Application September 29, 1934, Serial No. 53,436

Term of patent 3½ years

To all whom it may concern:

Be it known that we, Edgar E. Kahn and Louis Kanner, citizens of the United States of America, residing at New York city, in the county of New York, Borough of Manhattan and State of New York, have invented a new, original, and ornamental Design for Cosmetic Containers of which the following is a specification, reference being had to the accompanying drawing, forming a part thereof.

We claim:—

The ornamental design for a cosmetic container, as shown and described.

EDGAR E. KAHN.
LOUIS KANNER.
